UNITED STATES PATENT OFFICE.

JOSEPH M. BARRETT, OF FOSTORIA, OHIO, ASSIGNOR TO THE S-C REGULATOR MANUFACTURING COMPANY, OF FOSTORIA, OHIO, A CORPORATION OF OHIO.

TURBINE-PUMP GOVERNOR.

Application filed May 4, 1923. Serial No. 636,778.

This invention is concerned primarily with pump governors adapted to operate valves to vary the effective steam line to the pump. Recent developments in prime movers, such as are used in central power station plants, have brought about the use of steam under high pressures and high temperatures, the prevailing practice being to generate the steam in the boilers under from 350 to 10 500 pounds pressure and at temperatures ranging from 500 to 750 degrees Fahrenheit, superheat. The solution of the primary problem of generating power economically by such practices has introduced many other 15 problems in the development and design of auxiliary machinery used in the power plant and one of the most difficult problems has been to develop a pump governor for turbine-driven hydraulic pumps, such as are 20 used for feeding water to the boilers, against high pressures. It is desirable that the feed pump pressures be maintained at a constant excess over the boiler pressures, this excess pressure being dependent upon the relative 25 disposition of the boiler and the feed water pump. It is very important that this difference in the pressures be maintained constant regardless of momentary fluctuations in the steam pressure, or regardless of the varying 30 demands on the pump.

The general object of the present invention, therefore, is the provision of a turbine-driven pump governor, which will respond instantly in its regulatory action upon the feed water pressure to variations in the steam turbine pressure and effect this regulation in a smooth and gradual manner, yet with sufficient rapidity to respond to the extremely sensitive action of a turbine throttle.

40 A further object of my invention is the provision of a pump governor, adaptable to the maintenance of a constant difference or excess pressure in the feed water line over the steam turbine line, and which embodies 45 a frictionless mechanism adapted to function in a sensitive manner under extremely high temperatures and pressures. An additional object of the present invention is the provision of an extremely sensitive turbine pump 50 governor which involves simple construction characteristics thereby securing a continuity of service when operating under high pressures and temperatures, the construction of

the mechanism being such that no searching or so called hunting effect is present.

55 Other objects of my invention will be hereinafter set forth in the following description which refers to the accompanying drawings, illustrating a preferred embodiment thereof. The essential characteristics 60 are summarized in the claims.

In the drawing, Fig. 1 is a side elevation of my device; Fig. 2 is a cross sectional elevation thereof and is taken along the line 2-2 of Fig. 1; Fig. 3 is a cross sectional view taken substantially along the line 3-3 of Fig. 2; Fig. 4 is a cross sectional view taken substantially along the line 4-4 of Fig. 2; and Fig. 5 is a cross sectional view taken along the line 5-5 of Fig. 2.

70 My invention contemplates the use of a governor valve mechanism wherein the respective parts of the mechanism are completely encased and are arranged in a coacting manner to prevent friction caused from 75 rubbing of the respective parts. Such a mechanism involves the use of a pressure diaphragm acted upon one side by the feed water pressure and on the opposite side by the steam pressure of the boiler line, and a second 80 diaphragm exposed to the steam pressure on one side and to atmospheric pressure on the other side, and connected to the first diaphragm by fulcrum levers whereby a pressure on the steam side of the first-named 85 diaphragm may be exerted thereupon, which may always be in excess of the pressure on the hydraulic side of the diaphragm. I thereby obtain a governor mechanism which does not involve the use of springs or 90 weights to counterbalance the governor.

In Fig. 1, I show such a governor mechanism which comprises a valve body member 10, having a dividing wall 11, affording support for valve members 12 and 13 which coact with valve closure members 14 and 15 respectively. The latter members are mounted upon the upper end of a floating stem 17, which has the lower end thereof connected to a diaphragm 18, through a fulcrum 95 yoke 20 and pin 54. The valve stem 17 is disposed within an exteriorly ribbed casing member 22, having an upper flanged end 23 thereof secured in clamped relation to a flanged branch 24 of the valve body member 10. The lower end of the casing member 22

is flared, as indicated at 25, to provide a diaphragm chamber, and terminates in a flange 26 which is in clamped relation with the perimeter of the diaphragm 18. A bottom closure member 28 is secured in clamped relation with the flange 26 of the casing member 22 and comprises the hydraulic pressure side of the governor. A hydraulic line 29 leading from the boiler feed water line 10 of the pump serves to connect the interior of the member 28 to the boiler (not shown).

Attached to a branch 31 of the casing member 22, and which is formed adjacent the lower end thereof, is a fulcrum and lever housing or casing member 32, which is also a support for a second diaphragm casing member 33. The casing members 32 and 33 have the interiors thereof in communication with the interior of the casing member 22 through an opening 34. A second diaphragm 35, having the bottom side thereof exposed to the interior of the casing member 33 and the upper side thereof exposed to the atmosphere, is maintained in clamped relation 20 to the casing member 33 by a protecting cap member 37, suitably apertured, as indicated at 38, whereby the interior of this cap member is under atmospheric pressure.

By mechanically connecting the diaphragm 35 to the diaphragm 18 by means which is entirely disposed within the casing members 22, 32 and 33, and under the same pressure which prevails in the steam line, it is possible to obtain an excess pressure 30 upon the steam side of the diaphragm 18 opposing the counter-balancing hydraulic pressure which is exerted upon the under side thereof and within the member 28. This connecting means may comprise lever members pivotally mounted upon hardened knife-edge fulcrums, one of the fulcrums being adjustable from the exterior of the device whereby the desired excess pressure may be readily and accurately obtained within 40 the practical range of excess pressure adjustments of the governor mechanism.

As shown in Fig. 2, this mechanism embodies a lever member 39, having one end thereof acting upon a knife-edged fulcrum member 40 pivotally secured to the yoke member 20 by a screw member 40^a while the other end thereof extends between the arms of a fork member 41, the latter member rigidly carrying a fulcrum blade 42, which engages the end of the lever member 39 at the apex of a V-opening formed therein. The fork member 41 is connected to the diaphragm 35 through a rod member 43, which engages diaphragm clamping members 44 and 45, disposed on the inner and outer sides of the diaphragm respectively.

I obtain adjustment of the excess pressure exerted upon the lower diaphragm by the upper diaphragm by adjusting an intermediate pivot for the lever 39. Disposed inter-

mediate the ends of the lever member 39 therefore, and in slidable engagement therewith is an adjustable fulcrum bearing member 46, which engages the lever member 39 along a flat top surface thereof. This member is in the nature of a shoe mounted upon a yoke member 47, which is in slidable engagement with the side walls of the casing member 32. As illustrated in Fig. 5, the yoke member 47 is adjustably supported 70 upon the inner end of a screw member 50, which extends through the arms of the fork member 41, and outwardly through a packing joint 51, whereby the outer end thereof is disposed exteriorly of the device. To 80 further carry out the anti-friction design of this device, I also provide a fulcrum bearing member 52 upon the valve stem yoke 20, which engages a lower knife edge formed on the fulcrum block 40. This bearing block 85 52 may be secured to the yoke member by any suitable means, such as a pin member 53. The pin member 54 which connects the yoke member 20 to the diaphragm is rigidly fixed to flanged diaphragm clamping members 55 90 and 56, disposed upon the upper and lower sides of the diaphragm, respectively.

In the particular arrangement disclosed, the intermediate fulcrum for the lever 39, is adjusted to a position whereby the lever 95 arms have a two to one lever ratio, that is, when the hydraulic pressure has a tendency to raise the diaphragm 18 a certain distance upwardly, the hydraulic pressure has a tendency to move the diaphragm 35. It will 100 thus be seen that the area of the diaphragm 35 bears a definite relation to the area of the diaphragm 18 and the major division of the pressure governing characteristics of this device is determined by calculating the 105 respective areas, as will hereinafter be set forth, and the predetermined pressure regulating characteristics may be varied substantially twenty percent above or below the desired excess pressure by adjusting the pivot 110 block 46 in either direction from its two to one lever arm ratio position. I find the convenient formula for determining the proper areas of the diaphragms 18 and 35 respectively is as follows:—

If A^{18} equals the effective area of the diaphragm 18, and A^{35} equals the effective area of the diaphragm 35, and designating the desired excess pressure as Ep , and the turbine steam pressure as Sp , then

$$A^{35} = \frac{A^{18} \times Ep \times 2}{Sp}$$

In practice, a standard area is determined for the diaphragm 18, which therefore becomes constant, and the area of the diaphragm 35 is varied depending upon the particular excess pressure and immediate ranges thereof which may be desired.

I find that a governor made in accordance

with the foregoing disclosure has such extremely sensitive characteristics in responding to variations in the water feed and steam line pressures, that it is desirable to incorporate in the device, a dashpot mechanism which may act upon the diaphragm 18 and cause it to move smoothly and gradually and yet permit it to quickly respond to boiler pressure variations while preventing hunting or intermediate vibratory movements of the diaphragm. I accordingly extend the hydraulic pressure casing members 28 downwardly a sufficient distance, whereby the lower part thereof may comprise a cylinder adaptable for the reception of a dashpot 60, which may have an upwardly extending stem 61 secured to a diaphragm clamping member 56, by a coupling member 62.

The action of this dashpot may be regulated by permitting hydraulic pressure to be exerted upon the upper and lower ends thereof, and I therefore, provide a passageway 63 formed in the casing member 28, which establishes communication between the hydraulic pressure chamber and lower end of the piston member 60. This passageway may be regulated by a valve member 63 which may have the inner end thereof adjusted relative to a small opening 64, where 30 by the area of the passageway may be varied. This valve member 63 is in threaded engagement with the casing member 28 and locked in adjusted position by any suitable means, such as a lock nut member 65. A cap member 66 may be provided to completely shield the needle valve member 63 and the locking member 65.

The operation of the mechanism is as follows:—

When steam is admitted to the turbine line, the casing members 22, 32, and 33, rapidly fill with condensate until the casing member 22 has a water line which is substantially at the height of the radiating rib 22^a which is the third rib from the valve body 24. The radiating ribs formed on the casing member 22, serve to maintain the temperature of this condensate low relatively to the temperature of the turbine steam line, and all the mechanism disposed within the respective casing is thereby protected from the excessive superheat of this steam. The condensate is maintained at the level referred to by reason of a liberal passageway formed in a bushing member 70, which does not contract with the piston stem 17, but acts merely as a step in limiting the downward or opening movements of the valve members 14 and 15. The diaphragms 18 and 35, are therefore under a pressure which is equal to the steam pressure in the line but are completely insulated from the steam pressure.

The diaphragm 18 is deflected downwardly by this pressure and the diaphragm 35 is deflected upwardly thereby. The upward

movement of the latter, acts upon one end of the lever member 39 and causes it to exert an additional or excess pressure upon the diaphragm 18, through the fulcrum blade 40 and yoke member 20, secured to the valve members 14 and 15 and these valve members are thus drawn downwardly out of contact with their respective cooperating valve seat members 12 and 13. This condition prevails until the hydraulic pressure in the feed water line connected to the turbine driven pump, is equal to the steam pressure in the steam line leading to the turbine pump, plus the additional or excess pressure exerted upon the diaphragm 18 by reason of the upward movement of the diaphragm 35, and the action of the interconnecting mechanism disposed therebetween.

If it is desired to decrease this excess pressure within reasonable limits, the screw member 15 may be adjusted to cause the fulcrum block 46 to be shifted towards the valve stem casing 22, and the action of the lever upon the diaphragm 18 is decreased. If it is desired to increase the pressure, the fulcrum block 46 may be adjusted outwardly towards the outer end of the screw member 50 and the action upon the diaphragm 18 is increased.

My governor mechanism does not involve any springs, weights or sliding members and thereby avoids the introduction of such difficulties as wearing and sticking of the moving parts, and variations in the action of such members due to friction. The means for connecting the diaphragms to the valve members is entirely free of any sliding contact and there is an absence of packing glands or joints on all of the moving elements of my mechanism. Furthermore, the nature of the mechanism is such that the various pivoting means embodied therein, may comprise hardened knife-edge fulcrum blocks which are protected from the deteriorating effect of the superheated steam by reason of the fact that my entire counter-balancing mechanism is insulated from the steam by a condensate bath.

Some distinct advantages are to be found in the use of such a device in that its instantaneous response to variations in the steam line leading to the turbine pump effects a regulation in the feed water pressure to such an extent that pressure charts taken simultaneously of the steam line pressure and the feed water line or hydraulic pump pressure discloses two curves which are identical in their smallest details of variation, the curves being spaced apart a distance corresponding to the desired constant excess pressure to which the mechanism has been set. The use of my device eliminates pounding or water hammer in the feed water line, and prevents an over-feeding or under-feeding of the boilers when unusual demands

are made upon the steam line, and is extraordinarily instrumental in furthering the obtaining of proper heat balances in central power station operation.

5. What I claim is:—

1. In a pump governor, the combination of a valve, a valve member adapted to control the flow of steam to a turbine, a diaphragm exposed on one side to the pressure 10 of said steam and adapted to be exposed on the other side to the hydraulic pressure of the pump, a second diaphragm exposed to said pressure on one side and to atmospheric pressure on its opposite side, and means 15 connecting the two diaphragms in supplemental and coacting relation to said valve member whereby the valve member may be maintained open against a hydraulic pressure which is in excess of the steam pressure 20 exerted on the diaphragms.
2. In a pump governor, the combination of a valve member, a diaphragm, means connecting the diaphragm to the valve member, a second diaphragm and motion varying 25 means connecting the second diaphragm to the first diaphragm, whereby the action of one diaphragm may be in a direction opposite to the action of the other diaphragm and said diaphragm connecting means may 30 be thereby operated to exert different pressures in a common direction with the first named diaphragm.
3. In a valve, the combination of closure 35 means therefor, a diaphragm exposed to the pressure in the valve, a second diaphragm arranged to be exposed to said pressure, one of said diaphragms being adapted to be exposed to other than atmospheric pressure, the other of said diaphragms being adapted 40 to be exposed to atmospheric pressure, means connecting the first named diaphragm to said valve closure means, and other means connecting the second diaphragm to the first diaphragm in adjustable supplementary relationship.
4. In a pump governor, the combination 45 of a valve body member disposed in a steam line, a valve member disposed therein adapted to close the steam passageway extending through the valve body member, a casing secured to and depending from said valve body member and communicating with the steam line, a diaphragm secured to the lower 50 end thereof and exposed to steam pressure on one side and water pump pressure on the other side, a movable means for connecting the valve member to the diaphragm, said movable means being suspended within said 55 casing independently of the walls of the valve body member and said casing, a second diaphragm exposed to steam pressure and associated with the first diaphragm, connecting means between the diaphragms, said 60 means being completely enclosed in the cas-

ing, and means within the casing for varying the action of the second named diaphragm upon the first diaphragm whereby the forces due to steam pressure are integrated to oppose the force due to water pump pressure. 70

5. In a pump governor, the combination of a valve body member adapted to be connected in a steam line leading to the turbine of the pump, a valve member for interrupting a passageway extending through the 75 valve body member, a casing member adapted to retain a hydrostatic column, a pair of diaphragms and pressure varying means disposed therebetween, a fulcrum connection between the diaphragms and associated with 80 said pressure varying means, and a second casing member secured to the bottom of said first casing member whereby hydraulic pressure may be exerted upon the under side of the diaphragm closing the bottom of said first named casing member, and means disposed below said diaphragm and acting thereupon to retard vibratory movements 85 thereof.

6. In a pump governor, the combination of a valve body member adapted to be connected in a steam line leading to the turbine of a pump, a valve member for closing a passageway extending through the valve body member, a casing adapted to retain condensate, a diaphragm exposed to the condensate, a second diaphragm associated with the first diaphragm and arranged to respond in its movement to pressure on the condensate pressure varying means disposed between the diaphragms, including a fulcrumed connecting member disposed between the diaphragms, and a dashpot acting on one of said diaphragms to retard vibratory 95 movements thereof. 100

7. In a pump governor of the character described, the combination of a valve closing member, a diaphragm associated therewith to receive high water pressure on one side and to receive pressure on the other side from the steam line in which said valve member is disposed, and excess pressure means acting upon the steam side of the diaphragm including a second diaphragm having an area greater than the exposed area of the first named diaphragm whereby the excess pressure plus the steam pressure may equal the water pressure. 110 115

8. In a pump governor of the character described, the combination of a valve body member having a low and a high pressure chamber, a valve member closing communication between the respective chambers, a diaphragm exposed to high fluid pressure on one side, means connecting the valve member and the diaphragm, a second diaphragm adapted to deflect when the first named diaphragm deflects in response to another fluid pressure common to both diaphragms, and 120 125 130

means connecting the two diaphragms whereby deflection of the second named diaphragm will cause an excess pressure to be exerted in the same direction with the first named diaphragm, said means including a pivotally mounted member, and a mounting therefor, whereby adjustment of the mounting will vary the excess pressure exerted upon the first named diaphragm when the second diaphragm deflects.

9. In a valve, the combination of a diaphragm operated valve closure member, a diaphragm therefor exposed on opposite sides to different fluid pressures, a second diaphragm having an exposed area greater than the first diaphragm and exposed to the lesser of the fluid pressures exerted upon the first diaphragm, and means connecting the diaphragms whereby a deflecting movement of the second diaphragm will exert an excess pressure upon the first named diaphragm equal to the difference in fluid pressure thereon.

10. In a pump governor of the character described, the combination of a valve body member having a high and a low pressure chamber, a valve member closing communication between the respective chambers, a casing secured to the valve body member with the interior thereof in communication with the high pressure side of the valve body member, a diaphragm closing an opening in said casing, a second diaphragm closing a branch opening extending from said casing, a valve stem connecting the first named diaphragm with said valve member, said valve stem being movable independently of the walls of the casing, a fulcrum lever disposed within said branch opening and connected with one end of said valve stem and at the other end to said diaphragm, and adjustable fulcrum mounting therefor, and means extending from the exterior to the interior of the casing for varying the position of said fulcrum mounting.

11. In a pump governor of the character described, the combination of a valve body member having a high and a low pressure chamber, a valve member closing communication between the respective chambers, a casing secured to the valve body member with the interior thereof in communication with the high pressure side of the valve body member, a diaphragm closing the bottom of said casing member, a second diaphragm closing the opening of a branch extending from said casing, an interiorly disposed means connecting the diaphragms in supplemental relation with said valve member, including a fulcrum lever disposed within said branch, an adjustable fulcrum mounting therefor, and means for varying the position of said fulcrum mounting.

12. In a steam pump governor of the character described, the combination of a

valve body member, a valve controlled passageway extending thereto, a casing member secured to the valve body member with the interior thereof in communication with said passageway, said casing having openings closed by a pair of diaphragms, whereby pressure within the casing will deflect the diaphragms outwardly, means connecting the two diaphragms whereby outward movement of one diaphragm will cause additional pressure to be exerted in the same direction with the other diaphragm, said means including a fulcrum lever and a slidably mounted fulcrum block therefor, and means extending from the exterior to the interior of the casing for adjusting the position of said fulcrum block.

13. In a valve, the combination of a valve body member, a valve member controlling a passageway extending therethrough, a casing member secured to the valve body member with the interior thereof in communication with said passageway, said casing having openings closed by diaphragms, whereby pressure within the casing will deflect the diaphragms outwardly, and means connecting the two diaphragms whereby outward movement of one diaphragm will cause additional pressure to be exerted upon another diaphragm, said means including a fulcrum lever and a slidably mounted fulcrum block therefor, and means extending from the exterior to the interior of the casing for adjusting the division of said fulcrum block.

14. In a pump governor, the combination of a valve, a valve member adapted to control the flow of steam to a turbine, a movable member exposed on one side to the pressure of said steam and adapted to be exposed on the other side to the hydraulic pressure of the pump, a second movable member exposed to said pressure on one side and to atmospheric pressure on its opposite side and means connecting the two movable members to said valve member whereby the valve member may be maintained open against a hydraulic pressure which is in excess of the steam pressure exerted on the movable member.

15. In a valve, the combination of closure means therefor, a movable member exposed to the pressure in the valve a second movable member arranged to be exposed to said pressure, one of said movable members being adapted to be exposed to other than atmospheric pressure, the other of said members being adapted to be exposed to atmospheric pressure, means including a beam supported on points to eliminate friction for connecting the first named movable member to said valve closure means, and other means connecting the second movable member to the first movable member.

16. In a steam pump governor, the combination of a diaphragm operated valve

member, an operating diaphragm therefor, a second diaphragm arranged to deflect under a pressure which deflects the first named diaphragm, means including a member supported on bearings, one of said bearings being capable of manual adjustment along said member, for connecting the diaphragms whereby a deflecting movement of the second diaphragm will exert a variable excess pressure upon the first named diaphragm. 10

In testimony whereof, I hereunto affix my signature.

JOSEPH M. BARRETT.
